UNITED STATES PATENT OFFICE.

BERNARD H. ZIMMERMAN, OF UTICA, NEW YORK, ASSIGNOR, BY MESNE ASSIGNMENTS, TO UNION SPECIAL MACHINE COMPANY, OF CHICAGO, ILLINOIS, A CORPORATION OF ILLINOIS.

METHOD OF PRODUCING SEwed FABRICS.

No. 857,510.

Specification of Letters Patent.

Patented June 18, 1907.

Application filed November 20, 1903. Serial No. 181,970.

To all whom it may concern:

Be it known that I, BERNARD H. ZIMMERMAN, a citizen of the United States, residing at Utica, in the county of Oneida and State of New York, have invented certain new and useful Improvements in Methods of Producing Sewed Fabrics, of which the following is a specification.

My invention consists of certain improvements in making the neck portions of garments, the purpose of my invention being to facilitate the securing together of the overlapping ply or plies at the said neck portion and to provide a better finish than usual.

In the specification and claims, I shall for convenience refer to the overlapping plies of fabric as single plies, although the invention is, as indicated in the preceding paragraph, applicable to cases where the plies each consist of a number of thicknesses of fabric, hence the term "ply," as herein used, is intended to cover one or more thicknesses of fabric.

In the accompanying drawings: Figure 1 is a view illustrating the application of my invention to the production of the neck portion of a knitted garment; Fig. 2, is a front view of the neck portion of the garment after the completion of the process forming the subject of my invention; Fig. 3, is a rear view of the same; Fig. 4, is an enlarged diagram illustrating the relation of the securing mechanism to the fabric when the operation is about to begin.

In the manufacture of certain classes of underwear a knitted web is folded on the line of the shoulder so as to form back and front plies or folds 1 and 2, or such plies or folds are united on the line of the shoulders, and, in order to form the neck opening, the front ply or fold 2 of fabric is cut so as to form a central segment 3, which lies upon the back ply or fold 1 and is secured thereto around the edge, this ply being also secured to the back ply at the line of the original fold or at the points where the upper edges of the two plies have originally been secured together. Heretofore, in effecting this result it has been usual to first mark, upon the back ply, the line to be followed in cutting out the neck and then to form a row of stitches following this line so as to secure the segmental neck piece or fold to the back ply, after which the

front ply is cut, adjacent to the line of stitches, so as to free said front ply from the back ply and form the neck opening therein to be subsequently finished in any desired manner, the raw or cut edge of the segmental back fold being then covered by means of zigzag stitches so as to prevent exposure of the cut edge and impart a neat finish to this portion of the garment.

As the cut is made by hand its distance from the line of stitches depends upon the skill and accuracy of the operator and hence is likely to vary within wide limits, and, as the operator has only this preliminary line of stitches to serve as a guide in the formation of the covering stitches, the eye is again the only means for determining the position of said covering stitches in respect to the cut edge, hence irregularity in the disposition of such covering stitches must also result and it is impossible, under the present practice, to form a neat, uniform and attractive finish upon this portion of the garment. In the case of knitted fabrics moreover, the tendency of a cut edge is to curl up, hence it is always difficult to form a row of confining stitches evenly over such cut edge.

In carrying out my invention, I dispense with the usual preliminary row of stitches for securing the two plies of the fabric together and form the double row of connected stitches by an operation substantially simultaneous with the cutting operation, the needle or needles which constitute an element of the sewing mechanism bearing such relation to the cutter that the stitches formed by such needle or needles must necessarily be evenly spaced in respect to the cut edge, and as the sewing operation follows the cutting operation so closely that the cut edge has no opportunity to curl. I not only effect a saving of time, material and labor, as compared with the ordinary method, but produce a result, which, as to uniformity and neatness in appearance, it is impossible to produce by such ordinary method.

In carrying out my invention, I can use any form of sewing machine having two needles, or a zigzagging needle, for producing two rows of stitches side by side, either in chain or lock stitch, such needle or needles being combined with a looper, a shuttle, or other means for connecting said stitches, or

for interlooping them or for connecting them by means of an extra thread or threads on that side of the garment where the cut edge of the fold is presented. Such machines are 5 common in the art, and, in carrying out my invention, I add thereto a cutter acting in advance of the needle or needles, such cutter being preferably so constructed as to have a projecting sput or point for piercing the fold 10 of the fabric, as shown in Fig. 4, and traveling between the cut and uncut plies. With such a cutter is also employed, by preference, a deflecting plate for turning back that one of the cut edges which is not to be confined 15 to the back ply so that said edge will be out of the way of the stitch forming mechanism of the machine.

In Fig. 1, of the accompanying drawing, which is an inverted view of the parts as they 20 appear in practice, 4 represents the cutter, traveling between the two plies 1 and 2 and cutting the near ply 2, and 5 represents the deflector, this view showing the condition of the garment shortly after the operation has 25 been started and illustrating the closeness with which the formation of the securing stitches 6 follows the cutting operation.

Fig. 2, shows the neck portion of the garment after the operation has been concluded, 30 the segmental flap or fold 3 being secured to the back ply 1 of the garment by means of the connected rows of stitches, one row of stitches being formed in the double ply comprising both the back ply 1 and flap 3, and 35 the other row of stitches being formed in the single back ply only, the connections between the stitches overlapping and covering the cut edge of the flap, which occupies throughout a position midway between the two lines of 40 stitches.

Fig. 3, shows the back of the fabric, illustrating the two lines of stitches whereby the securing of the flap 3 to the back ply of the garment has been effected, and Fig. 4 illustrates how, in beginning the operation, the 45 piercing point of the cutting knife penetrates the fold of the garment so as to enter between the two plies and cut only the under ply, the outer cut edge of said under ply being then directed away from the needles 7 by the deflector 5.

Many different ways of connecting the two lines of stitches may be adopted, such connection being effected either by interlocking and interlooping the stitches 6 or by connecting the two lines of stitches by means of an additional thread or threads. 55

Although I have described my invention in connection with the manufacture of the neck portion of a garment, it is capable of application to any line of manufacture in which overlapping portions of fabric comprising either a single ply or a number of plies have to be secured together on a curved line, and the curved edge of one ply has to be covered 60 and protected by the stitches. 65

Having thus described my invention, I claim and desire to secure by Letters Patent:

1. The method herein described, of uniting overlapping plies of fabric, consisting in inserting a knife between the plies and cutting but one of the same on a predetermined line, and by a substantially simultaneous operation deflecting one of the cut edges, securing one of said cut edges to the lower ply by 70 overstitching, one line of said overstitching passing through and uniting the two plies and the other line passing through the single 75 ply only, the cross threads of the overstitching covering the last mentioned cut edge; 80 substantially as described.

2. The method herein described, of necking underwear, consisting in folding the web of fabric to form overlapping plies, inserting a knife at the fold which is thereby caused to 85 enter between the plies, and cutting one of the same, cutting said ply on a predetermined line, and by a substantially simultaneous operation deflecting one of the cut edges and securing the other cut edge to the lower ply 90 by a double row of stitches, one row passing through the two plies and the other through the single ply, and uniting said rows of 95 stitches, so as to cover the last mentioned cut edge; substantially as specified.

In testimony whereof, I have signed my name to this specification, in the presence of two subscribing witnesses.

BERNARD H. ZIMMERMAN.
